UNITED STATES PATENT OFFICE.

JOHN P. FERRITER, OF BOSTON, MASSACHUSETTS, AND EARLY E. STRADLEY, OF WEST ORANGE, NEW JERSEY.

TELEGRAPH-PRINTER SYSTEM.

Application filed November 13, 1925. Serial No. 68,868.

The object of this system is to transmit telegraph signals at a high rate of speed, either by radio or over a wire, and to print the received signals without the necessity for synchronizing the transmitting and receiving apparatus.

Existing telegraph printer systems and apparatus are used for perforating tape and transmitting signals, using either the five unit code or the continental code, depending on the type of printer system utilized. The perforated tape is caused to actuate the transmitter, which sends the signals over the line in the usual manner. At the receiving station, the received signals pass through the coils of the receiving relay and actuate it in the usual manner. At this point, we depart from the usual system of causing the receiving relay to actuate one or more printers. Instead, we cause the relay armature contacts to interrupt a tone produced by a tone generator, a buzzer or other suitable device, as shown in Figure 1.

With the foregoing and other objects in view, the invention consists in the combination and arrangement of parts hereinafter described, certain embodiments thereof being illustrated in the accompanying drawings, in which:

Figure 1 is a diagrammatical showing of the improved system.

Figure 2 is a detailed diagrammatical showing of the relation between the recording and reproducing element and the remainder of the system.

Referring more particularly to the drawings, in Figure 1, C and C¹ are the armature contacts of the receiving relay R. Contacts C and C¹ are connected electrically in series with tone generator G and the coils of a telephone receiver T. The diaphragm D of receiver T is encased directly above the recorder R¹ on a dictating phonograph in such a manner that, when the receiver diaphragm D is caused to vibrate, it transmits the vibrations to the stylus S of recorder R¹. Stylus S rests on a moving wax cylinder W on which it makes a record of the vibrations of diaphragm D in the form of small indentations. It will be seen from the foregoing description that, when contacts C and C¹ are closed, an alternating current from generator G will pass through the coils of receiver

T, actuating its diaphragm and causing a record to be placed on the wax cylinder W and, when contacts C and C¹ are open, due to the action of relay R in responding to line signals, no current will pass through the receiver coils and no record will be made on the cylinder. In this manner, signals transmitted from the distant station X actuate the relay R at receiving station Y and cause a record to be made on cylinder W.

In order to translate the signals recorded on cylinder W, the cylinder is placed on a dictating phonograph equipped with a special reproducer which rectifies the signals and actuates a telegraph relay. This telegraph relay passes the signals to the printer distributor and causes the printer to print the characters originally transmitted from Station X.

The special reproducer referred to is described fully in a separate patent application. Its action is as follows, as shown in Figure 2, in which A is a small bar, pivoted at one end and carrying a contact near the other end. B is a flat spring, rigidly fastened at one end, carrying a contact near the other end facing the contact on bar B, and attached by a stiff wire C to the inertia bar D which carries the reproducing stylus E. F is the phonograph record.

The action of this device is as follows: when the reproducing stylus passes over the series of indentations on the record forming a signal, the spring B is caused to vibrate. Due to the inertia of the bar A, the contact on it does not follow exactly the movements of the contact mounted on the spring B. These two contacts are connected in series with a battery G and the coils of the relay H to be operated. When the reproducing stylus E passes over a signal on the record F, the resulting vibration of spring B introduces sufficient resistance between the contacts on A and B to practically stop the flow of current through the coils of relay H, but when the stylus E passes over a blank space on the cylinder, the contacts on A and B remain closed and current passes through the coils of H and actuate its armature. The operation of the local contacts of relay H may then be caused to actuate a printer in the usual manner.

Some of the advantages of our system over

other telegraph printer systems are that signals may be transmitted at a high rate of speed without regard to the mechanical limitations of the receiving printers, as the printers are entirely disassociated from the line. Synchronism between the sending and receiving stations is not necessary, as the cylinders containing the received signals may be placed on a dictating phonograph at any time and reproduced at any rate of speed suitable for the printer which they operate. The cylinders may be run any desired number of times or may be caused to operate any desired number of printers. This is useful when more than one copy of the messages are required.

Having thus described our invention, we claim:

A system of printing telegraphy comprising a telegraph printer and a relay, means for recording the received signals on a phonograph record, and means for re-running the record and reproducing said signals by causing the imposed signals to actuate said relay, the armature contacts of said relay being adapted to control the action of said telegraph printer. 20
